UNITED STATES PATENT OFFICE

JOSEPH F. KASPER, OF LOUISVILLE, KENTUCKY

DESIGN FOR A KITCHEN CABINET

Application filed June 16, 1930. Serial No. 36,050. Term of patent 14 years.

To all whom it may concern:

Be it known that I, JOSEPH F. KASPER, a citizen of the United States, residing at Louisville, in the county of Jefferson and the State of Kentucky, have invented a new, original, and ornamental Design for Kitchen Cabinets, of which the following is a specification, reference being made to the accompanying drawings, which form a part thereof.

Fig. I is a front elevation of the cabinet, showing my new design.

Fig. II is a side elevational view thereof.

I claim:

The ornamental design for a kitchen cabinet as shown.

In testimony whereof I have hereunto set my signature this eighteenth day of April, 1930.

JOSEPH F. KASPER.
